United States Patent Office.

LOUIS COTÉ, OF ST. HYACINTH, CANADA.

Letters Patent No. 109,300, dated November 15, 1870.

IMPROVEMENT IN APPARATUS FOR TRIMMING HEELS OF BOOTS AND SHOES.

The Schedule referred to in these Letters Patent and making part of the same.

To all whom it may concern:

Be it known that I, LOUIS COTÉ, of St. Hyacinth city and county, Province of Quebec, in Canada, have invented an Improved Hand Apparatus for Trimming Heels of Boots and Shoes; and I do hereby declare that the following, taken in connection with the drawings which accompany and form part of this specification, is a description of my invention sufficient to enable those skilled in the art to practice it.

This apparatus is designed for use by hand with the boot and shoe-holding machine shown and described in the United States Letters Patent No. 104,560, granted to me June 21, 1870, or with any suitable apparatus, which, while it holds a boot or shoe firmly, is provided with a center-pin to which to connect my trimming apparatus, so that it can be moved around the convex outline of a heel, and a guide-plate located on the heel-tread to supply one of the two guides needed, the other guide being found on the counter of the shoe itself.

In the drawings—

Figure 1 shows in full lines a side view of my improved apparatus, and

Figure 2 shows in full lines a plan of the same, both as applied in the act of trimming a heel.

The dotted lines shown in said figures represent parts of a boot or shoe to be operated upon, the guide-plate *k* upon the tread of the heel, and the piece *j*, which receives the guide-plate, and is provided with the pivot or center, about which my apparatus is carried.

The lever *a* is the piece to which a workman applies most of the force necessary to make the knife perform its function of cutting.

At one end of said lever an eye or socket is made to fit upon the pivot-pin *b*, the other end of the lever being supplied with a suitable handle, *c*.

To the lever *a* is pivoted, at *d*, the lever *e*, having one end connected to the handle *c* by a spring, *f*, the other end of lever *e* being kept forced, by the spring *f*, against the radius-arm *g*, which has a pivot-hole, which receives one end of the knife-carrier, one end of which passes through said hole, and has secured between said arm *g* and a nut, *h*, on the end of the knife-carrier, a spring, *i*, which admits of endwise movement of the knife.

The other end of the knife-carrier, which is extended some distance from the knife for convenience, is provided with a cross-handle, *l*, by which the operator keeps the edge of the knife at a proper angle to

the path of its movement, the apparatus requiring in use the application of both hands of the workman.

The knife-blade *m*, in practice, is adjustably and removably attached to the carrier *n*, so that it may be readily removed for sharpening, and suitably fixed in position.

The carrier *n* has connected with it a guard and gauge, *o*, arranged so that its location may be changed by manipulation of screw *p*, which passes through a slot in the carrier *n*.

The back of this piece *o* rests against the counter *q*, and the end edge of *o* bears against the sole *r*, on that surface nearest the counter, the yielding of spring *i* compensating for any variation of height of the heel from front to rear, and keeping the end edge of guard *o* in close contact with the sole *r*.

The end of the knife or of the knife-carrier near the radius-arm *g* is kept pressed against the heel-tread *k* by the action of spring *f*, which yields enough to compensate for the varying distances which the knife is obliged to take from the heel center in passing around it.

The other part of the knife is kept in place, and the back of guard *o* pressed against the counter, by force applied to the handle *l*.

From the foregoing it will be seen how a workman can rapidly and perfectly shave smoothly a rough heel attached to a lasted boot or shoe, by making use of the described apparatus in connection with any device or apparatus or machine which presents a pivot or center for the lever *a*, a tread guide-plate, *k*, and means for holding the lasted boot or shoe in position, one continued movement and one cut around the heel effecting the object of reducing the rough heel to the desired shape and size, the counter being at the same time protected from risk of being cut by the knife.

To vary the tension of the spring *f*, I prefer, in practice, to connect one end thereof to handle *c* by means of a clamp-screw adjustable in a slot cut through the handle.

For heels of various heights, the guide and guard *o* is adjusted on the knife-carrier *n*, so as to cover more or less of the edge of the knife.

I claim—

A hand-operated heel-trimming tool, constructed as described.

LOUIS COTÉ.
